UNITED STATES PATENT OFFICE

CHARLES R. HARRY, OF FREDERICKTOWN, OHIO, ASSIGNOR TO THE J. B. FOOTE FOUNDRY COMPANY, OF FREDERICKTOWN, OHIO, A CORPORATION OF OHIO

MOLD

Application filed March 30, 1927. Serial No. 179,633.

This invention relates to molds, more particularly relating to molds designed for molding cement blocks and the like in which an ejecting mechanism is employed for ejecting the blocks from the mold.

An object of the invention is to provide a mold of this character which will be simple in construction and effective in operation.

A further object is to improve the ejecting mechanism whereby great leverage is exerted at the beginning of the ejecting action and the action of ejecting the block gradually accelerated until the block clears the mold.

A further object of the invention is to provide an ejecting mechanism so constructed that the molded article is brought slowly to rest without shock at the end of the ejecting action and the ejecting mechanism automatically locked without the employment of catches or other separate locking devices.

Other objects will be apparent from the following description, claim and statement of advantages.

In the accompanying drawings:

Fig. 1 is a side elevation of a mold embodying the improvements.

Fig. 2 is a section on the line *a—a* of Fig. 1.

Fig. 3 is a section on the line *b—b* of Fig. 2.

Referring to the drawings, 1 represents the side frames of the molding apparatus which are constructed in any suitable manner, but are shouldered along their forward and rear edges to receive transversely extending bars 2 to which are secured by the cap screws 3 a series of spaced-apart longitudinally extending horizontal supporting pieces 4 which form supports for the cores 5 which are arranged vertically in the mold box 6. This mold box is open at the top and is provided with a removable spout 7 to guide the wet material into the interior of the mold box. Before the mold box is filled with the material to be molded, there is inserted therein a platen 8, this platen acting as a part of the ejector mechanism now to be described.

Carried by each of the side frames 1, midway its length is a stationary vertical guide rod 9 upon each of which is slidably mounted a head 10; the side frames having laterally offset channels 1^a to accommodate these guide

rods. Each head is formed with an integral sleeve 11 slidably mounted on the corresponding rod 9 and is also formed with an overhanging flange 12 and with laterally projecting arms 13. To the arms 13 are secured vertical push rods 14, the upper ends of which project between the supports 4 with their extreme upper ends reduced as indicated in dotted lines at 14^a with the reduced ends inserted loosely in openings in the platen 8. The arms 13 and sleeve 11 are preferably connected by webs 15 for strengthening purposes.

Journalized in the lower portions of the frame pieces 2 is a transverse shaft 16 to one end of which is connected an operating lever 17. Fastened to this shaft are a pair of cam fingers 18, each having a comparatively long cam surface. The effective low portion of each cam finger it will be seen is located close to the center of the shaft 16 while the extreme outer end of the cam arm is formed on the arc of a circle whose center is the center of the shaft 16. Co-operating with each cam arm is a comparatively long lifter arm 19, each lifter arm being pivotally mounted on a cross shaft 20 carried by the frame pieces. The free end of each lifter arm carries a roller 21 which lies immediately beneath the overhanging flange 12 of the head 10, this roller being journaled upon a stud 22 secured to the lifter arm, with the head of the stud countersunk in the inner face of the roller as shown in Fig. 3.

In operation, after the platen 8 has been inserted into the mold, and with the ejector mechanism in the position shown in full lines in Fig. 2, the mold is filled with the wet cement. To eject the molded article after it has become sufficiently set, the operator grasps the handle 17 and turns the shaft 16 which causes a powerful leverage to be exerted by the lower effective surface of each of the cams 18 upon the arms 19 which in turn through their rolls 21 lift the heads 10, push rods 14 and platen 8 to eject the cement block or other article from the mold. By reason of the form of the cams 18, a tremendous leverage is exerted upon the arms 19 at the beginning of the ejecting operation, and the cement of the block, or other molded

article, is gradually accelerated until it clears the mold. At the end of the raising movement of the parts, the nose 18^a of each of the cams will engage the lifter arms, in the manner shown in dotted lines in Fig. 2, and hold the parts in raised position so as to allow for the removal of the platen 8 together with the molded article carried thereon. By manipulating the lever 17, the cams will be caused to free the lifter arms and allow the head and push rods to drop by gravity to their lower position.

Having thus described my invention, I claim:

15 In a mold, a supporting frame, a mold box supported thereby and open at one end, a pair of heads slidably carried by said frame, a platen in said mold box supported by said heads, each head being provided with an over-hanging portion, a pair of lifter arms, one for each head, pivoted on said support with the free end of each lifter arm arranged to engage the under side of said over-hanging portion of its corresponding head, an operating shaft, and a pair of cams secured to said shaft, one for each lifter arm.

In testimony whereof, I have hereunto set my hand this 28 day of March, 1927.

CHARLES R. HARRY.
